UNITED STATES PATENT OFFICE.

OWEN H. SUMPTER AND JESSE G. SHEFFER, OF MITCHELLVILLE, IOWA.

BOLSTER REPAIR STAKE.

Application filed March 14, 1927. Serial No. 175,167.

The object of our invention is to provide a bolster repair stake of simple, durable, and comparatively inexpensive construction.

A further object of our invention is to provide a repair stake of the type described which can be conveniently applied to a bolster from which the stake has been broken.

Still a further object is to provide arms on our repair stake which extend along the sides of the bolster and beneath the wagon bed for securely fastening the repair stake to the bolster.

Still a further object is to provide a means on our repair stake to engage the end of the bolster which further braces the stake to prevent the upper end from being forced outwardly.

Still a further object is to provide a repair stake which can be applied to a bolster (from which the original stake has been broken) with the aid of a saw, a wrench and a brace and bit.

Still a further object is to provide extension stake loops on our repair stake, the fastening means of which serve to hold the parts of the stake in assembled position.

With these and other objects in view, our invention consists in the construction, arrangement and combination of the various parts of our bolster repair stake, whereby the objects contemplated are attained, as hereinafter more fully set forth, pointed out in our claims, and illustrated in the accompanying drawings, in which:

Figure 1 is a perspective view of our improved repair stake.

Figure 2 is a side elevation of the same illustrating it applied to a bolster from which the original stake has been broken; and

Figure 3 is a detail sectional view taken on the line 3—3 of Figure 2.

On the accompanying drawing I have used the reference numeral 10 to indicate generally the bolster of a wagon. The bolster 10 may be either the front or rear bolster inasmuch as our repair stake can be applied to either with equal efficiency. Ordinarily the bolster 10 is longer than illustrated as indicated by the end 12 which is shown by dot and dashed lines. The original stake as constructed on the general type of wagons now in use has a tenon formed on its lower end designed to fit in a mortise cut in the bolster 10. At the most, such a stake is rather a make-shift device and very frequently breaks

off in the mortise and tenon joint. If in breaking off it splits the end 12 of the bolster, it is almost impossible to attach another stake to the end of the bolster. To overcome this objection, we have provided our repair stake with means for securing it to the side of the bolster under the wagon bed.

Our improved repair stake comprises a pair of side members 14 formed of cast steel or malleable iron or the like. Side members 14 have inwardly projecting arms 16 adapted to fit along the sides of the bolster 10. The arms 16 are provided with openings 18. A pair of extension stake loops 20 are provided pivoted to the side members 14 by 70 rivets or the like 22.

A filler block 24 is positioned between the side members 14 and held in position by the rivets 22. It will be noted that the end 26 of the filler block 24 extends below the arms 16.

When the original stake of the bolster 10 is broken off, the bolster is sawed off on the line 28 at the outermost extremity of the wagon box. Our repair stake is then positioned 80 with the end 26 of the filler block 24 engaging the sawed off end of the bolster. Holes 30 are then drilled through the bolster 10 in alignment with the openings 18 of the arms 16. Bolts 32 are then positioned through 85 the openings 18 and 30 and the nuts 34 are applied to them for securely clamping the arms 16 to the sides of the bolster 10.

The arms 16 help in a great measure to prevent the upper ends of the stake from being bent outwardly. However the end 26 of the filler block 24 serves a substantial purpose for further bracing the repair stake.

It will be noted that an outward tendency against the upper end of the stake forces the 95 end 26 against the end of the bolster for serving as a rigid brace.

The side members 14 are additionally reinforced by the thickened portions 36 cast along the side members and the arms 16. 100

From the foregoing description it will be obvious that we have provided a repair stake which is very efficient and which can be easily and quickly used to replace the original stake when broken off.

Some changes may be made in the arrangement and construction of the parts of our bolster repair stake, without departing from the real spirit and purpose of our invention, and it is our intention to cover by our claims, 110

any modified forms of structure or use of mechanical equivalents, which may be reasonably included within their scope.

We claim as our invention:

- 5 1. A bolster repair stake comprising an upright portion and a horizontal portion, means for securing said horizontal portion including a pair of arms and an insert secured therebetween, said insert to the sides
10 of a bolster, said upright portion extending below the horizontal portion of the stake and adapted to rest against the end of the bolster.
2. A bolster repair stake comprising vertical and horizontal arms, said horizontal
15 arm adapted to extend beneath the bed of the wagon and the vertical arm including an insert adapted to engage the end of the

bolster and serve as a stake to position said bed and means for securing said insert to said vertical arm, said means comprising extension stake loops and fastening means extending through the loops, the arm and the insert for holding these parts assembled. 20

3. A device of the class described comprising a frame having parallel arms, said arms 25 being vertical to serve as a stake and having horizontally extending portions for securing the device to a bolster and an insert secured between said parallel arms and extending to a position abutting against the end of the 30 bolster.

Des Moines, Iowa, March 1, 1927.

OWEN H. SUMPTER.
